(57) **CLAIM**

The ornamental design for a wireless emergency system controller, as shown and described.

DESCRIPTION

FIG. 1 is a first isometric view of the wireless emergency system controller;

FIG. 2 is a second isometric view of the wireless emergency system controller;

FIG. 3 is a front elevation view thereof;

FIG. 4 is a rear elevation view thereof;

FIG. 5 is a left side elevation view thereof; and

FIG. 6 is a right side elevation view thereof; and,
FIG. 7 is a top plan view of the wireless emergency system controller.

The subject ornamental design is for a wireless emergency system controller—sometimes referred to as a WES Connect device (see FIGS. 1-7) In general, WES is provided in construction, industrial and commercial property locations to facilitate emergency responses involving fire, safety and medical situations amongst responding personnel and automated building systems. The controller of the present subject design conforms with wireless US specification technology that enables a WES emergency evacuation and medical alert system to be installed quickly and moved around as required without damaging the building. Unlike hard wired systems, WES can be used in the most complex of locations where traditional hard-wired alarms would be impractical or cost-prohibitive.
